United States Patent [19]
Amey, deceased et al.

[11] Des. 245,949
[45] * Oct. 4, 1977

[54] OTTOMAN

[76] Inventors: Aubrey Amey, deceased, late of New York, N.Y., by Greta A. Beckner, administratrix, 1703 W. Case Road, Columbus, Ohio 43220

[] Term: 14 Years

[21] Appl. No.: 718,313

[22] Filed: Aug. 27, 1976

Related U.S. Application Data

[62] Division of Ser. No. 574,109, May 2, 1975.

[51] Int. Cl. .... D6—01
[52] U.S. Cl. D6/36

[58] Field of Search D6/32, 33, 34, 35, 36;
297/461, 462, 175

[56] References Cited

U.S. PATENT DOCUMENTS

2,838,098	6/1958	Fuerst	D6/36 X
D. 86,020	1/1932	Gibson	D6/32
D. 233,190	10/1974	Shearin et al.	D6/32

Primary Examiner—Bruce W. Dunkins
Attorney, Agent, or Firm—George B. Finnegan

[57] CLAIM

The ornamental design for an ottoman, as shown and described.

DESCRIPTION

The drawing is a front perspective view showing the ottoman design. The end of the ottoman not shown is a mirror image of the end shown.

U.S. Patent

Oct. 4, 1977

Des. 245,949